UNITED STATES PATENT OFFICE.

BRITTON E. BYRD, OF DURHAM, NORTH CAROLINA, ASSIGNOR TO MILL DEVICES COMPANY, OF DURHAM, NORTH CAROLINA, A CORPORATION OF NORTH CAROLINA.

MACHINE FOR MAKING AND PACKING CIGARETTE-WRAPPERS.

1,274,510.

Specification of Letters Patent.

Patented Aug. 6, 1918.

Application filed February 10, 1917. Serial No. 147,838.

To all whom it may concern:

Be it known that I, BRITTON E. BYRD, a citizen of the United States, residing at Durham, in the county of Durham and 5 State of North Carolina, have invented a new and useful Machine for Making and Packing Cigarette-Wrappers, of which the following is a specification.

The device forming the subject matter of 10 this application is adapted to be employed for making packages of small papers of the kind which constitute a part of a cigarette.

The invention aims to provide novel 15 means for slitting strips of cigarette paper longitudinally, to form ribbons, the ribbons being superposed upon each other and being inclosed in a wrapper.

Another object of the invention is to provide novel means for cutting the superposed 20 ribbons and the wrapper into lengths, thereby to form the packages.

Another object of the invention is to provide novel means for assembling and collecting the packages.

25 With the above and other objects in view which will appear as the description proceeds, the invention resides in the combination and arrangement of parts and in the details of construction hereinafter described 30 and claimed, it being understood that changes in the precise embodiment of the invention herein disclosed can be made within the scope of what is claimed, without departing from the spirit of the invention.

35 In the accompanying drawings:—

Figure 1 shows in top plan, a machine embodying the improvements hereinafter described.

Fig. 2 is a fragmental perspective view 40 showing a portion of the rotary receiver to which the packages of cigarette papers are delivered ultimately;

Fig. 3 is an end elevation of a machine including the present improvements;

45 Fig. 4 is a longitudinal section of the machine, parts appearing in elevation;

Fig. 5 is a sectional detail showing a portion 50 of the rotary receiver, and delineating particularly, the latch whereby the receiver is prevented from rotating at times; and

Fig. 6 is a fragmental elevation showing 55 the rolls which crease the wrapper, so that the same may be engaged readily around the ribbons which are cut up to form the cigarette paper packages.

In carrying out the present invention

there is provided a supporting structure including a base 1 and upstanding side plates 2 which may be shaped as required. Adjacent the rear end of the machine, the side 60 plates 2 are connected by a horizontal platform 3, as shown best in Fig. 4. Mounted on the platform 3 near to the rear end of the machine are bearings 4. The side plates 2 are connected by a cross bar 5 having notches 6 in its rear edge. The lower ends of shafts 7 are journaled in the bearings 4, and the reduced upper ends 8 of the shafts 7 are received for rotation in the notches 6 of the cross bar 5. Vertically moving latch bearings 9 are pivoted to the cross bar 5, and in the latch bearings 9, the reduced upper ends 8 of the shafts 7 are received. Spring washers 100 may be interposed between the upper ends of the shafts 7 and the cross bar 5, to the end that the shafts 7 may not rotate too freely, when the cigarette paper is drawn therefrom, in a manner to be described hereinafter.

70 Mounted on the platform 3 in front of the bearings 4 are bearings 10. The side plates 2 are connected by a cross bar 11. Vertical shafts 12 are mounted in the cross bar 11 and in the bearings 10. The shafts 12 carry cutting instrumentalities, whereby the sheets 75 of cigarette paper are cut into ribbons. The cutting instrumentalities preferably include sleeves 14 and cutting disks 15 alternating with the sleeves, these elements being mounted on the shafts 12 to turn thereon.

80 A horizontal shaft 16 is mounted in the side plates 2 and is adapted to receive a roll of paper which forms a folder for the cigarette papers. Mounted in the side plates 2 and disposed above the shaft 16 are guide rods 17. Disposed below the guide rods 17 and journaled in the side plates 2 is a roller 18. A roller 19 is similarly mounted in the side plates 2 below the roller 18. The roller 18 is provided, as shown in 100 Fig. 6, with grooves 21 coacting with creasing ribs 20 constituting a part of the roller 19.

85 In front of the guide rods 17, the side plates 2 are connected by a support 22, carrying a folder 23. Shafts 24 and 25 are journaled in the side plates 2 ahead of the folder 23. The shafts 24 and 25 are provided with co-operating compression rollers 26 which rotate with the respective shafts 105 24 and 25, these shafts being operatively connected by intermeshing gear wheels 27

which are shown in Fig. 3. The shaft 24 may be provided at one end with fixed and loose pulleys 28, or with any other suitable driving means whereby motion may be imparted to the shafts 24 and 25, and therefrom to other moving parts which will be set forth hereinafter. Journaled in the side plates 2 in front of the rollers 26 is a shaft 29, a shaft 30 being similarly mounted, below the shaft 29. The shafts 29 and 30 are connected by intermeshing gear wheels 31. The shaft 29 carries a roller 32 coacting with a roller 33 carried by the shaft 30. The roller 32 has longitudinally extended cutting blades 34 received in longitudinal grooves 35 in the roller 33. The shafts 24 and 29 carry sprocket wheels 36 around which is trained a sprocket chain 37.

The mechanism above described constitutes the means whereby the sheets or strips of cigarette paper are cut longitudinally into ribbons, the ribbons being superposed, a wrapper being applied to the ribbons, and the ribbons and the wrapper being severed transversely to form packages. The description of the machine will be temporarily suspended at this point, in order that the operation of the structure above alluded to may be set forth.

In practical operation, rolls of cigarette paper, indicated at 81, are mounted on the shafts 7. The paper of these rolls 81 is extended between the sleeves 14 and the disks 15, and by the disks 15 is cut into ribbons 83. The ribbons 83 are given a quarter turn, and pass between the rods 17 in superposed relation. A roll 84 of the paper which is to form the wrapper is mounted on the shaft 16. The paper on this roll 84 is extended between the rollers 18 and 19. The paper in the roll of wrapping 84 is considerably wider than the ribbons 83 of cigarette paper, the wrapping paper and the superposed ribbons 83 passing through the folder 23, being drawn therethrough by the coacting compression rollers 26. The ribs 20 on the roller 18, coacting with the grooves 21 in the roller 19, crease the wrapping paper from the roll 84 longitudinally, and the folder 23 laps the longitudinal edges of the wrapping paper over onto the superposed ribbons 83, as the wrapping paper and the ribbons pass through the folder. By the rollers 26, the wrapping paper and the ribbons 83 are fed between the roller 32 and the roller 33, the blades 34 on the roller 32 coacting with the grooves 35 in the roller 33 to cut the superposed ribbons and the wrapper which incloses them, into packages. At this point it may be incidentally observed that, in Fig. 2, a plurality of these packages 85 are shown in place in a rotatable receiver which will be described hereinafter.

Resuming the description of the machine, it may be stated that the base 1 carries an

upright support 38 at the upper end of which is located a guide 39. A slide 40 is mounted for horizontal reciprocation in the guide 39. The forward end of the slide 40 is provided with an inclined prow 41. Secured to the slide 40 is a laterally offset arm 42, the outline of which appears best in Fig. 1. The forward end of the arm 42 is beveled off vertically as shown at 43 in Fig. 3. Depending from the slide 40 is a finger 44, adapted to be engaged by the arms of a star wheel 45 fixed to a shaft 46 which is journaled in the support 38. The shaft 46 is connected by means of intermeshing beveled pinions 47 with a stub shaft 48 mounted in one of the side plates 2. There are sprocket wheels 49 on the stub shaft 48 and on the shaft 30 of the roller 33, the sprocket wheels being operatively connected by a sprocket chain 50. The slide 40 is retracted by a spring 51, one end of which is attached to the slide, the other end of which is attached to a post 52 upstanding from the base 1.

Mounted on the base 1 are standards 53 and 54, the standard 54 being provided in its upper end with a notch or keeper 55, the function of which will be made manifest hereinafter. Mounted in the standards 53 and 54 is a rigidly fixed shaft 56 on which a rotatable receiver is journaled.

The receiver includes a pair of side plates 57, connected by a drum 58. A coiled spring 59 surrounds the shaft 56 between the standards 53 and 54, one end of the spring being attached to the drum, and the other end of the spring being attached to the shaft. The spring 59 constitutes a means for rotating the receiver in the direction of the arrow A in Fig. 3. The side plates 57 of the rotatable receiver are united by top plates 60 and by bottom plates 61, as shown best in Fig. 2, the top plates 60 being somewhat shorter than the bottom plates 61. The construction is such that at intervals about its periphery, the rotatable receiver is provided with compartments denoted by the numeral 62. Located in the compartments 62 are compression springs 63 coacting with followers 64.

One of the side plates 57 is provided at its periphery with notches 65 receiving a holder in the form of a bar 66. Journaled on the holders 66 exteriorly of the side plate 57 which has the notches 65 are rollers 67. The holders 66 are rigidly secured to the ends of the long arms 68 of bell cranks 69 fulcrumed at 70 on one of the side plates 57. Pivoted at 71 to the short arms 72 of the bell cranks 69 are pawls 73 coacting with rack bars 74 mounted to slide in guides 75 carried by that side plate 57 which is provided with the notches 65. The inner ends of the rack bars 74 are beveled as shown at 76. The right hand side plate 57 of the rotatable receiver (Fig. 2) is provided, as 130

shown in Fig. 5, with laterally extending arms 77 to which latches 79 are pivoted as shown at 78, the latches 79 swinging in openings 80 formed in the side plates 57. 5 As shown in Fig. 2, the latches 79 project beyond the outer face of the side plate 57 which has the notches 65, the protruding ends of the latches 79 being adapted to coact, one after another, with the notches or seats 10 55 in the standard 54, to prevent the rotatable receiver from turning under the action of the spring 59. The beveled ends 76 of the rack bars 74 engage beneath the protruding ends of the latches 79, to permit a rotation 15 of the receiver, in a manner which will be described hereinafter.

It has been pointed out hereinbefore that the ribbons 83 of cigarette paper and the wrapper 84 which incloses the ribbons, are severed by the blades 84 on the roller 32 to 20 form packages 85. These packages 85 drop one after another into the compartment 62 of the rotatable receiver, as indicated by the arrow B in Fig. 2, and lie flat on the bottom 25 plate 61. When a package has been deposited on the bottom 61 as above described, the slide 40 advances. The beveled end 43 of the arm 42 on the slide engages the roller 67 on the end of the holder 66 and elevates 30 the holder, the bell crank 69 tilting on its fulcrum 70, and the arm 68 of the bell crank moving upwardly. After the holder 66 has been raised, the prow 41 of the slide 40 engages beneath the package which lies flat on 35 the bottom 61 of the rotatable receiver, and turns the said package up into a vertical position, one package after another being advanced against the follower 64, and the spring 63 being compressed. After a package 40 has been deposited in the vertical position of Fig. 2, and when the slide 40 is retracted, the holder or bar 66 drops by gravity into a position in front of the package, as Fig. 2 will make manifest.

45 Each time that the bell crank 69 is tilted vertically on its fulcrum 70 by the action of the arm 42 on the slide 40, the rack bar 74 is advanced one notch. Ultimately, and after a predetermined number of packages 50 85 have been compressed against the follower 64, the beveled end 76 of the rack bar 74 engages between the protruding end of the latch 79, and lifts said end of the latch out of the notch or keeper 55 in the 55 standard 54. The rotatable receiver then turns, under the action of the spring 59, until another latch 79 engages with the keeper 55. Thus, a new compartment 62 is presented to receive the severed packages from 60 the rolls 32 and 33, and is disposed in such a position that the slide 40 may exercise its function as hereinbefore set forth.

65 The operation of the structure has been dealt with step by step in connection with the various component mechanisms, but,

briefly considered by way of résumé is as follows.

By the action of the rollers 26, the ribbons 83 and the wrapping paper 84 are drawn forwardly. The wrapping paper is 70 decreased by the rolls 18 and 19 and is disposed about the superposed ribbons 83, due to the action of the folder 23. The rollers 26 advance the superposed ribbons 83 and the wrapping into the field of the blades 75 34, which, coöperating with the grooves 35 in the roller 33, cut the material into packages. The packages pass in the direction of the arrow B of Fig. 2 into the compartment 62 of the rotatable receiver. The guide 40 80 turns the packages 85 up vertically and deposits them behind the holder 66. When the bell crank 69 is tilted by the coöperation between the beveled end 43 of the arm 42 on the slide 40 and the roller 67 on the 85 arm 68 of the bell crank, the pawl 73 advances the rack bar 74, and ultimately, the beveled end 76 of the rack bar disengages the latch 79 from the keeper or notch 65 in the standard 54, so that the rotatable receiver can turn under the action of the spring 59 and present an empty compartment 90 62 to be filled.

The drives are as follows:—

From a prime mover, rotation is imparted 95 to the shaft 24 by the driving means 28. From the shaft 24, rotation is imparted to the shaft 25 by the intermeshing gear wheels 27, the rollers 26 being actuated in this manner. The shaft 24 is operatively connected to the shaft 29 by the sprocket wheels 36 and the sprocket chain 37, the intermeshing gear wheels 31 imparting rotation to the shaft 30 from the shaft 29. The sprocket wheels 49 and the chain 50 drive the stub 100 shaft 48 from the shaft 30, and rotation is imparted to the shaft 46 which carries the star wheel 45, by the intermeshing beveled pinions 47. The arms of the star wheel 45 coöperating with the finger 44 on the slide 110 40, advance the slide, the slide being retracted by the spring 51 which is put under tension when the slide is advanced. As hereinbefore stated, the rotatable receiver is actuated by the spring 59 when the latch 115 79 is disengaged from the keeper 55 in the standard 54.

Having thus described the invention, what is claimed is:—

1. In a device of the class described, mechanism for simultaneously advancing superposed ribbons and a wrapper; means for folding the wrapper on the ribbons; mechanism for severing the ribbons and the folded wrapper to form packages; a movable 120 receiver having compartments; a feeder coacting with the packages to advance the same into the compartments; means for moving the receiver to present the compartments successively to the feeder; mechanism for 130

actuating the feeder; and means for operatively connecting all of said mechanisms, whereby one may drive the others.

2. In a device of the class described, means for simultaneously advancing superposed ribbons and a wrapper; means for folding the wrapper on the ribbons; mechanism for severing the ribbons and the folded wrapper transversely to form packages; a movable receiver having compartments; a feeder coacting with the packages to advance the same into the compartments; means for moving the receiver to present the compartments successively to the feeder; mechanism for actuating the feeder, and means for driving the actuating mechanism from the severing mechanism.

3. In a device of the class described, means for simultaneously advancing superposed ribbons and a wrapper; means for folding the wrapper on the ribbons; means for creasing the wrapper longitudinally as it is advanced and before the wrapper is folded; mechanism for severing the ribbons and the folded wrapper transversely to form packages; a movable receiver having compartments; a feeder coacting with the packages to advance the same into the compartments; means for moving the receiver to present compartments successively to the feeder; mechanism for actuating the feeder; and means for driving the actuating mechanism from the severing mechanism.

4. In a device of the class described, means for simultaneously advancing superposed ribbons and a wrapper; mechanism for folding the wrapper on the ribbons; means for severing the ribbons and the folded wrapper transversely to form packages; a receiver having compartments; means for supporting the receiver for rotation; a feeder coacting with the packages to advance the same into the compartments; means for rotating the receiver to present the compartments successively to the feeder; mechanism for actuating the feeder, and means for driving the actuating mechanism from the severing mechanism.

5. In a device of the class described, means for simultaneously advancing superposed ribbons and a wrapper; means for folding the wrapper on the ribbons; mechanism for severing the ribbons and the folded wrapper transversely to form packages; a movable receiver having compartments; a feeder coacting with the packages to advance the same into the compartments; mechanism for moving the receiver to present successive compartments to the feeder; a latch mechanism coöperating with the receiver to hold each compartment in operative relation to the feeder; mechanism for actuating the feeder; means for driving the actuating mechanism from the severing mechanism;

and means carried by the feeder and coacting with the latch mechanism to move the latch mechanism into an inoperative position, thereby to permit the receiver to move responsive to the means for moving the receiver.

6. In a device of the class described, means for simultaneously advancing superposed ribbons and a wrapper; means for folding the wrapper on the ribbons; mechanism for severing the ribbons and the folded wrapper transversely to form packages; a receiver having compartments; means for supporting the receiver for rotation; a feeder coacting with the packages to advance the same into the compartments; means for rotating the receiver to present the compartments successively to the feeder; mechanism for actuating the feeder; means for driving the actuating mechanism from the severing mechanism; a latch coöperating with the receiver to prevent a rotation of the receiver; and means carried by the feeder and coacting with the latch, to move the latch into an inoperative position, whereby the receiver will be rendered responsive to the means for rotating the receiver.

7. In a device of the class described, mechanism for simultaneously advancing superposed ribbons and a wrapper; means for folding the wrapper on the ribbons; mechanism for severing the ribbons and the folded wrapper transversely to form packages; a movable receiver having compartments; a feeder coacting with the packages to advance the same into the compartments; means for moving the receiver to present the compartments successively to the feeder; a device for actuating the feeder; and means for driving the actuating device from one of said mechanisms.

8. In a device of the class described, a first shaft adapted to support a roll of paper; a cutter disposed approximately parallel to the shaft and constituting means for severing the roll of paper into ribbons; a second shaft disposed approximately at right angles to the first shaft and adapted to support a roll of wrapper; a folder; means for drawing the wrapper and the ribbons through the folder; mechanism for severing the wrapper and the ribbons into packages, after the ribbons and the wrapper have passed through the folder; and means for imparting a twist to the ribbons and for superposing the ribbons, between the first specified cutter and the folder.

9. A device of the class described, constructed as set forth in claim 1, in combination with a latch device coöperating with the receiver to hold each compartment in operative relation to the feeder; and means carried by the feeder and coacting with the latch device to move the latch device into

an inoperative position, thereby to permit the receiver to move responsive to the means for moving the receiver.

10. In a machine for making books of cigarette paper, the combination of means for supplying a cover strip, means for supplying a plurality of superposed wrapper strips, an annularly recessed roll and a co-acting roll having peripheral portions entering the opposed recessed roll and co-acting therewith to longitudinally crease the cover strip and provide folding lines at opposite sides of the superposed wrappers, and fold-forming means for turning the opposite sides of the cover strip along the folding lines over each other and upon the wrapper strips.
15. In a machine for making books of cigarette paper, the combination of means for supplying a cover strip, means for supplying a plurality of superposed wrapper strips, an annularly recessed roll and a co-acting roll having peripheral portions co-acting with the recessed roll to longitudinally crease the cover strip at opposite sides of the wrapper strips and provide folding lines, and fold-forming means for turning the opposite sides of the cover strip over each other and upon the wrapper strips,

20. with presser rolls at the end of the fold-forming means, between which rolls the folded cover strip and inclosed wrapper strips are passed and by which the respective strips are drawn between the creasing rolls and through the fold-forming means, substantially as described.
25. 12. In a machine for making cigarette paper books, the combination of means for supplying a cover strip, means for supplying a plurality of superposed wrapper strips,

a pair of rolls adapted to longitudinally crease the cover strip at opposite sides of the wrapper strips, and rolls for pressing the folded cover strip and inclosed wrapper strips and drawing the same from the supplies through the creasing rolls and fold former, with a fold former interposed between the creasing and pressing rolls for turning the opposite sides of the cover strip over each other and upon the wrapper strips, and means for cutting the folded cover strip and inclosed wrapper strips into book lengths.

13. In a machine for making cigarette paper books, the combination of means for supplying a cover strip, means for supplying a plurality of superposed wrapper strips, a pair of rolls adapted to longitudinally crease the cover strip at opposite sides of the wrapper strips, and means for pressing the folded cover strip and inclosed wrapper strips and drawing the same from the supplies through the creasing rolls and fold former, with a fold former interposed between the creasing and presser rolls and having a flaring end adjacent the creasing rolls and sides converging toward the presser rolls and turned in and overlapping, rotary cylinders for cutting the folded strip and inclosed wrapper strip into book lengths, and means for rotating the pressing rolls and cutting cylinders.

In testimony that I claim the foregoing as my own, I have hereto affixed my signature in the presence of two witnesses.
